UNITED STATES PATENT OFFICE.

PERCY H. THOMAS, OF UPPER MONTCLAIR, NEW JERSEY, ASSIGNOR TO COOPER HEWITT ELECTRIC COMPANY, OF HOBOKEN, NEW JERSEY, A CORPORATION OF NEW JERSEY.

GAS OR VAPOR ELECTRIC APPARATUS.

1,156,825.

Specification of Letters Patent.

Patented Oct. 12, 1915.

Application filed September 12, 1912. Serial No. 719,923.

To all whom it may concern:

Be it known that I, PERCY H. THOMAS, a citizen of the United States, and resident of Upper Montclair, county of Essex, State of New Jersey, have invented certain new and useful Improvements in Gas or Vapor Electric Apparatus, of which the following is a specification.

My invention relates to the starting and operating of mercury vapor lamps and especially such lamps when proportioned to run in their normal light giving condition with relatively high temperatures at the mercury electrodes. Such mercury vapor lamps are characterized by tightly sealed envelopes containing mercury and exhausted of air and other foreign gases. Such lamps have peculiar characteristics of their own. When the mercury constituting the electrodes is cold, the pressure of mercury vapor is small and a very low voltage is sufficient to support the flow of current when once started, although a high resistance to starting of current flow exists, as is well known. As the apparatus warms up the electrodes become hotter and the pressure of the mercury vapor within the container is higher and the operating voltage rises, while the starting resistance becomes less. Thus the temperature at which the lamp finally steadies will be determined by the relative effectiveness of the heating and cooling means in the device as a whole, but more particularly as these elements effect the temperature of the mercury electrodes. Since the heating effect will vary with change of circuit voltages and to a certain extent with change of air temperatures, drafts, etc., the actual operating temperature of the lamp is likely to vary from time to time. This change in operating temperature will cause a considerable corresponding change in pressure and voltage.

One object of my invention is to minimize these changes, as will be pointed out.

In the drawings Figures 1 and 2 represent different views of a self regulating lamp, Fig. 3 a different view and a supply circuit, and Fig. 4 shows another form of lamp adapted to start without movement of the container and Fig. 5 a modification. Fig. 6 shows a circuit for utilizing lamps of the character here proposed.

Figs. 1, 2 and 3 show the lamp in the

non-operating position. The lamp is composed of a tight container, having electrodes 6 and 7, a V shaped light giving portion 1, two condensing chambers 2, 2 and a body of mercury 8, 8 serving to fill the electrode chambers and to connect the electrodes when the apparatus is in the position shown in Fig. 1. The floats 9, 9 are to protect the seals from the action of the mercury and to prevent the too ready transfer of heat from the hot electrode surface to the seals where the current is brought through the envelop. The line A B is the section line indicating the point at which the section shown in Fig. 2 is taken. The container may be of many substances, for example any kind of glass that will stand the temperature at which the lamp is to run. When the lamp is to run at relatively high temperatures quartz may be used. The operation of this lamp is as follows. When the lamp is in the position shown in Fig. 1, voltage is applied to the terminals and the lamp tipped into the position shown in Fig. 2. The separation of the mercury into two parts in the V shaped portion, when current is passing, overcomes the starting resistance of the lamp and the flow is established in the vapor path. The mercury will now stand at the same height in the chambers 2, 2 and in the V portion 1, but as the lamp heats up from the current flow, the pressure in the V portion will become the higher and the mercury will rise in the chambers 2, 2 until finally as the lamp reaches normal temperature, the level of the mercury in the V portion will be level with the opening into the chambers 8 or even below this point. Now any further increasing of the pressure in the V portion will cause vapor to escape from this portion into the chambers 2, 2 where it will be condensed and thus in effect will greatly increase the cooling surface, for up to this point the chambers 2, 2 have acted only at a great disadvantage in cooling the electrodes. It is clear that with this adjustment once the point of escape of the vapor has been reached that even a considerable increase in the amount of heat generated, as by an increase in the supply voltage or current will not be able to increase the internal pressure in the lamp and the voltage absorbed therein. This is very important when lamps are run in series circuits for if

one lamp of a series tends from structural variations or other particular local conditions to take a higher temperature than the others, its pressure will rise over theirs and this will in turn increase its heat loss and cause a further generation of excess heat and a greater rise of temperature and so on until the lamp goes out from excessive voltage or the whole series receives too little current. This is particularly important in this type of lamp because the lamps have a characteristic tending to show a constant current for all voltages. I have shown this lamp as connected in such a series circuit, 10 being a source of constant current and 11 being other series devices, as for example other lamps like that already described herein.

Fig. 4 shows a device adapted to be started without the movement of the container. In this lamp, 17 is the light giving portion; 2, 2, are two chambers at the ends of the tube, the whole being hermetically closed. 6 and 7 are two starting electrodes and 18 is an additional connection adapted to cut out the heating coil 15 after starting. In each of the chambers, 2, 2, is present a body of mercury covering the U shaped dip at the ends of the tube 17. The parts 9 are protecting floats, which serve to control the water hammer and to prevent overheating of the seals from high temperature of the electrode surfaces. The operation of this figure is as follows: At the start, a certain amount of gas pressure exists over the mercury columns 25, 25, and the chambers 2, which force the mercury to fill the tube 17 completely or at least so that the circuit is completed therethrough. When the generator 19 is excited a current flows through the coil 15, the electrode 6, through the mercury path in the tube 17, through the electrode 7 back through the other series devices 20, to the generator again. When the coil 15 is sufficiently hot, the mercury in the pocket 14 will vaporize to some extent which will cause a bubble to appear at the top of the tube 17, thereby separating the mercury into two parts. This separation will start a flow of current to the vapor path which flow of current will heat the electrodes, increase the separation between the mercury columns in the tube 17 and finally force it down until at the equilibrium point vapor begins its escape from the tube 17 into the chambers 2, 2, which will be the stopping point of the increase in pressure as has already been pointed out in connection with Figs. 1, 2 and 3. Meanwhile the mercury in being pressed back from the tube 17 is simultaneously connected to the electrode 18 and the electrode 6 thus cutting out the starting coil 15. The regulation of this apparatus on varying voltages and temperature conditions is similar to that of Figs. 1, 2 and 3. Should it be

necessary in further controlling the pressure regulating features of either of these lamps, contactions or other means of checking the transfer of heat from the mercury electrode surface from the tube 17 to the chambers 1 70 may be employed. For example, a float such as the float 9 can be used for the purpose. Obviously, if the heat is not conveyed in material quantities through conduction from the tube 17 to the mercury 25 in the chamber 2 before vapor begins to escape from the tube 17 a more sharply defined limit to the maximum pressure attainable will be secured.

In Fig. 5 I show a modification of the apparatus of Fig. 4, wherein direct atmospheric pressure is admitted to each chamber 2, 2 at the top through the porous plug 13 set in the outlet 12. This plug while admitting the passage of air under pressure will 80 serve to restrain the mercury itself from escaping from the bulb. If a suitably purified mercury be used in this device and if the container be properly treated beforehand to move occluded gas this device may be put in 85 operation without special pumping.

Fig. 6 shows a constant potential circuit adapted to supply lamps of the character described in this application. These may be run either single across the mains from the 90 constant potential generator 23 as at 21 or two or more in a series group as shown at 22. The lamp shown in the present invention is adapted for use on either alternating or direct current. When used on alternating 100 current it is desirable that in the device of Fig. 4 the coil 15 heat the top of the mercury columns in the tube 17 to a very considerable temperature before starting the actual flow of current in the vapor.

It is understood that while the devices shown have been described as lamps this invention is applicable to other forms of apparatus and applicant wishes to cover his inventions in its broadest aspects.

Other materials than mercury may be used for the electrode material, it being essential, however, to most of these lamps that the electrode material be liquid.

I claim as my invention:

1. A mercury vapor lamp comprising a W-shaped container, the central portion constituting a light giving-path and the end portions enlarged to act as condensing chambers, mercury in the lower portions of 115 said container acting as electrodes and as seals between the center portion and the end portions in the non-operating and in the subnormal condition of the lamp, said end portions acting as condensing chambers 120 during the steadyng operations when the mercury vapor pressure in the central portion of the condenser causes an escape of vapor to said condensing chambers.

2. In a vapor apparatus, steadyng means 130

comprising a main operating portion, electrodes therein and supplementary condensing surface normally closed from said main portion, in combination with means responsive to pressure above normal in the operating portion permitting escape of vapor from the operating portion to the supplementary condensing surface.

3. A vapor device, comprising three parts, 10 namely, a central portion containing mercury and two condensing chambers, and means including a W shaped container and pivoting means permitting movement of the container to separate the mercury in said 15 central portion into two electrodes and thereafter to enable vapor to escape from said central portion to the condensing chambers on any excess of pressure above a definite minimum.

20 4. The method of regulating the vapor pressure in the vapor path of a high pressure mercury vapor apparatus, which consists in utilizing the excess mercury vapor pressure accompanying an abnormal rise in 25 the temperature of the lamp to open a free passage for the escape of the mercury vapor into a fresh condensing space.

5. A mercury vapor apparatus comprising a sealed container exhausted to a high degree of purity and a central light-giving portion normally filled with mercury in the non-operating position, and means for utilizing outwardly generated heat to establish a vapor path in said central portion and inwardly generated pressure to limit the further development of said pressure but only when a certain predetermined minimum is reached.

6. A mercury vapor device comprising a main operating chamber and supplemental 40 cooling means, said cooling means being normally inoperative in combination with means responsive only to a pressure in said main chamber greater than normal for rendering operative said supplemental cooling 45 means.

Signed at New York, in the county of New York, and State of New York, this 9th day of September, A. D. 1912.
